CLAIM

The ornamental design for a display screen or portion thereof with animated graphical user interface, as shown and described.

DESCRIPTION

FIG. 1 is a front view of a first image of a first embodiment of an display screen or portion thereof with animated graphical user interface showing my new design;

FIG. 2 is a front view of a second image thereof;

FIG. 3 is a front view of a first image of a second embodiment of an display screen or portion thereof with animated graphical user interface showing my new design;

FIG. 4 is a front view of a second image thereof;

FIG. 5 is a front view of a first image of a third embodiment of an display screen or portion thereof with animated graphical user interface showing my new design; and,

FIG. 6 is a front view of a second image thereof.

In the first embodiment, the appearance of the transitional image sequentially transitions between the images shown in FIGS. 1 through 2. In the second embodiment, the appearance of the transitional image sequentially transitions between the images shown in FIGS. 3 through 4. In the third embodiment, the appearance of the transitional image sequentially transitions between the images shown in FIGS. 5 through 6. The process or period in which one image transitions to another image forms no part of the claimed design.

The broken lines shown in the drawings represent portions of the display screen or portion thereof with animated graphical user interface that form no part of the claimed design.
